UNITED STATES PATENT OFFICE.

MARSHALL C. LEFFERTS, OF NEW YORK, N. Y., ASSIGNOR TO THE ELECTRIC CUTLERY COMPANY, OF NEWARK, NEW JERSEY.

DESIGN FOR A RAZOR-HANDLE.

SPECIFICATION forming part of Design No. 21,014, dated August 25, 1891.

Application filed July 13, 1891. Serial No. 399,409. Term of patent 7 years.

To all whom it may concern:

Be it known that I, MARSHALL C. LEFFERTS, a citizen of the United States, residing in the city of New York, in the county and State of

5 New York, have invented and produced a new and original Design for Handles of Razors, of which the following is a specification, reference being had to the accompanying drawing, illustrating my design.

10 My design consists of the intaglio-rilievo ornamental figure *a* at the butt-end of the handle and an ornamentation *b*, consisting of a shaded and cloudy ground-work running

from near the middle to the other end of the handle and having forms representing heavy 15 only bodies in rilievo upon the said cloudy ground.

What I claim is—

A design for handles of razors, consisting of the figure *a* and the ornamentation *b*, substantially as shown.

MARSHALL C. LEFFERTS.
